UNITED STATES PATENT OFFICE.

HENRY WATERHOUSE SIMPSON, OF TORONTO, ONTARIO, CANADA.

DESIGN FOR A PHOTO-MOUNT.

No. 38,585.

Specification for Design.

Patented May 28, 1907.

Application filed March 8, 1907. Serial No. 361,410. Term of patent 7 years.

To all whom it may concern:

Be it known that I, HENRY WATERHOUSE SIMPSON, a subject of the King of Great Britain, and a resident of the city of Toronto, in the county of York, in the Province of Ontario, Canada, have invented a new, original, and ornamental Design for Photo-Mounts, of which the following is a specification, reference being had to the accompanying drawing, forming part thereof.

The figure is a plan view of a photo mount, showing my new design.

I claim:

The ornamental design for a photo mount, as shown.

HENRY WATERHOUSE SIMPSON.
